[57] CLAIM

The ornamental design for a whirlpool bath, as shown and described.

DESCRIPTION

FIG. 1 is a front perspective view of a whirlpool bath showing my new design;

FIG. 2 is a top plan view thereof;

FIG. 3 is a front view thereof;

FIG. 4 is a left side view thereof;

FIG. 5 is a right side view thereof;

FIG. 6 is a back view thereof;

FIG. 7 is a left perspective view thereof; and,

FIG. 8 is a perspective view of a whirlpool bath showing my new design, the broken line showing of the shower skirt surround being for illustrative purposes only and forming no part of the claimed design.

The bottom view is plain and unornamented.
